UNITED STATES PATENT OFFICE.

ROBERT JAMES WISNOM, OF VIRGINIA CITY, NEVADA.

ELECTRODE.

No. 872,878.

Specification of Letters Patent.

Patented Dec. 3, 1907.

Application filed October 3, 1906. Serial No. 337,305.

To all whom it may concern:

Be it known that I, ROBERT JAMES WISNOM, a subject of the King of Great Britain, residing at Virginia City, in the State of Nevada, have invented a certain new and useful Electrode; and I do hereby declare the following to be a full, clear, and exact description of the invention, such as will enable others skilled in the art to which it appertains to make and use the same.

This invention relates to electro-metallurgical apparatus and more particularly to the positive terminals used in the precipitation of precious metals from cyanid or like solutions.

An object sought to be attained is the prevention of the formation of impurities in the electrolyte as is the case where metallic anode is used.

It is further desired to provide an anode that will have a longer period of usefulness than those at present in use.

A further object is to provide an anode of this class wherein the metallic terminal will be so situated that it will not be attacked by the electrolyte.

In the partially broken away perspective accompanying and forming part of this specification, reference numeral 1 designates a sack of canvas or other suitable material having vertical lines of sewing 2, extending to within a short distance of the top, thus dividing the sack into a number of vertical pockets connected at their tops to a horizontal transverse pocket. The pockets are packed tightly with a metallic oxid, preferably peroxid of lead in a granular form. A conducting wire 3 is placed in the horizontal pocket and the granular filling is pressed tightly in contact therewith by strips of wood 5 placed on each side of the pocket and clamped together by means of bolts 6. The ends of strips 5 may be allowed to project beyond the sides of the bag 1 and rest on supports placed over the tank where the anode is used. Vertical strips 7 may be fastened to one or both sides of the bag 1 to prevent it

sagging out of shape and coming directly in contact with the cathode.

In the operation of this invention, any number of the anodes with their corresponding cathodes being suspended in an electrolyte, current is caused to flow into wire 3, whence it passes into the granular filling and through the electrolyte to the cathode, depositing the metals from the solution thereon. In order to prevent the electrolyte acting upon the wire 3, the anode is submerged only to a point a short distance below the level of the wire.

I claim:

1. An anode comprising a metallic oxid and a support for the same formed of vegetable fibers.
2. An anode comprising peroxid of lead in a granular form and a support for the same formed of vegetable fibers.
3. An anode comprising a non-conducting envelop divided into a number of vertical pockets, a transverse pocket connecting them at the top and a metallic oxid inclosed in said pockets.
4. An anode comprising a non-conducting envelop divided into a number of vertical pockets with a transverse pocket connecting them at the top, a metallic oxid inclosed in said pockets and a wire in said transverse pocket.

5. An anode comprising a non-conducting envelop divided into a number of vertical pockets, a transverse pocket having a wire therein, a metallic oxid inclosed in said pockets and means for compressing the contents of said pocket around said wire.

In testimony whereof I have signed my name to this specification in the presence of two subscribing witnesses at Virginia City, in the State of Nevada, this 11th day of September, A. D. 1906.

ROBERT JAMES WISNOM.
